UNITED STATES PATENT OFFICE

147,353

DESIGN FOR AN ORPHREY OR SIMILAR ARTICLE

Otto A. Scheurmann, Bayside, N. Y.

Application November 9, 1946, Serial No. 134,651

Term of patent 7 years

(Cl. D3—32)

To all whom it may concern:

Be it known that I, Otto A. Scheurmann, a citizen of the United States of America, residing in Bayside, county of Queens, and State of New York, have invented a new, original, and ornamental Design for an Orphrey or Similar Article, of which the following is a specification, reference being had to the accompanying drawing, forming part thereof.

In the drawing:

The figure is a plan view of the orphrey, embodying the design.

I claim:

The ornamental design for an orphrey or similar article, substantially as shown.

OTTO A. SCHEURMANN.
